Primary Examiner — Rhea Shields(74) *Attorney, Agent, or Firm* — Jon L. Woodard; Woodard International Law(57) **CLAIM**

The ornamental design for a package for hygiene articles, as shown and described.

DESCRIPTION

The patent or application file contains at least one drawing executed in color. Copies of this patent or patent application publication with color drawing(s) will be provided by the Office upon request and payment of the necessary fee.

In FIG. 1 is a perspective view of a package for hygiene articles, showing my new design;

FIG. 2 is another perspective view thereof;

FIG. 3 is another perspective view thereof;

FIG. 4 is another perspective view thereof;

FIG. 5 is another perspective view; and,

FIG. 6 is another perspective view.
